UNITED STATES PATENT OFFICE.

ADELAIDE M. PORTER, OF GREENWICH, CONNECTICUT, ASSIGNOR TO HUYLER'S INC.,
OF NEW YORK, N. Y., A CORPORATION OF NEW YORK.

DESIGN FOR A CONFECTIONERY BOUQUET.

56,308.

Specification for Design.

Patented Sept. 14, 1920.

Application filed April 9, 1920. Serial No. 372,681. Term of patent 14 years.

To all whom it may concern:

Be it known that I, ADELAIDE M. PORTER, a citizen of the United States, and resident of Greenwich, county of Fairfield, State of Connecticut, have invented a new, original, and ornamental Design for a Confectionery Bouquet, of which the following is a specification, reference being had to the accompanying drawings, forming part thereof.

Fig. 2 is a side view of my new design. The objects in clusters are candies.

I claim:

The ornamental design for a confectionery bouquet, substantially as shown.

Signed at New York, county and State of New York, this 31st day of March, 1920.

ADELAIDE M. PORTER.
